MEMORANDUM INDEX

Robert E. Gordenier, St. Paul, Minn., assignor to Brown & Bigelow, St. Paul, Minn., a corporation of Minnesota

Application September 26, 1949, Serial No. 5,170

Term of patent 14 years

(Cl. D74—1)

To all whom it may concern:

Be it known that I, Robert E. Gordenier, a citizen of the United States, residing in St. Paul, county of Ramsey, and State of Minnesota, have invented a new, original, and ornamental Design for a Memorandum Index, for which the following is a specification, reference being had to the accompanying drawing forming part thereof:

The dominant features of my design reside in those portions shown in full lines.

I claim:

The ornamental design for a memorandum index, as shown and described.

ROBERT E. GORDENIER.
